PORTABLE ELECTRIC GENERATOR

Jack E. Bullock, Van Nuys, Calif., assignor to Bendix Aviation Corporation, South Bend, Ind., a corporation of Delaware

Application February 5, 1957, Serial No. 44,757

Term of patent 14 years

(Cl. D26—5)

Fig. 1 is a perspective of a portable electric generator, showing my new design; and

Fig. 2 is a perspective view thereof showing the opposite end and side.

The bottom is conventional.

I claim:

The ornamental design for a portable electric generator, as shown and described.
